(57) CLAIM

The ornamental design for a shoe sole, as shown and described.

DESCRIPTION

FIG. 1 is a perspective view of a shoe sole showing my new design;

FIG. 2 is a second perspective view thereof; and,

FIG. 3 is a bottom view thereof.

The broken line showing of the remainder of the shoe sole is for illustrative purposes only and forms no part of the claimed design. The unshown portion of the shoe sole forms no part of the claimed design.

1 Claim, 3 Drawing Sheets

FIG. 3
